UNITED STATES PATENT OFFICE.

AUGUST H. SCHWAN, OF MOUNDRIDGE, KANSAS.

TWINE-HOLDER.

SPECIFICATION forming part of Letters Patent No. 529,756, dated November 27, 1894.

Application filed May 14, 1894. Serial No. 511,148. (No model.)

To all whom it may concern:

Be it known that I, AUGUST H. SCHWAN, of Moundridge, McPherson county, Kansas, have invented certain new and useful Improvements in Twine-Holders, of which the following is a full, clear, and exact description, reference being had to the accompanying drawings, forming a part hereof.

My invention relates to twine-holders of that class which, after the twine is drawn downward to the counter and used and broken, automatically elevates or raises the dangling or pendent portion of the twine a suitable distance above the counter so that it will not be in the way of the clerk, and the object of the invention is to produce a device of this character which is easy to manipulate, and which is simple, durable and inexpensive of construction.

With this object in view, the invention consists in certain peculiar and novel features of construction and combinations of parts, as hereinafter described and claimed.

In order that the invention may be fully understood, reference is to be had to the accompanying drawings, in which—

Figure 1. is a perspective view of a twine-holder embodying my improvements, and showing the same provided with a ball of twine and supported in operative position. Fig. 2. is a vertical sectional view of the same. Fig. 3. is a detail perspective view of the various parts detached, and Fig. 4. is a horizontal sectional view enlarged of the weight-carrying tube.

In the said drawings, 1 designates a ball of twine, which is wound in the usual manner upon the frusto-conical tube or sleeve 2, of paste-board.

3 designates a conical shell, which diametrically corresponds in size to the internal diameter of the tube 2, and this shell has its longitudinal margins arranged a slight distance apart, so as to form the opening or passage 4. The shell 3 is fitted upon or incloses the cylindrical tube 5, and has its upper end secured to and a short distance below the upper end of said tube in any suitable manner. The tube 5 has its lower end closed, and

is formed with a longitudinal and external groove 6, extending vertically from its upper to its lower end, and is also provided with an

eye 7, the object of which is hereinafter explained. A supporting bracket 8, of the form shown, or of any other suitable or preferred configuration, is provided with an eye 9 at its upper end, which engages a hook 10, depending from the ceiling or other suitable elevated position, and carried by and projecting vertically upward from the lower and adjacent ends of the arms of said bracket, is a segmental supporting-plate 11, which is of frusto-conical form in side view, and corresponds in size to the internal diameter of the conical shell 3, and the longitudinal margins 65 of said supporting-plate 11 are apart a distance slightly exceeding the diameter of the cylindrical tube 5, as shown at 12. The cylindrical tube 5 is recessed in its upper margin or end to form the oppositely disposed notches 13 and 14; the notch 14 being situated in vertical alignment with the opening or space 4, between the longitudinal margins of said shell, and communicating with the upper end of the longitudinally extending groove 6, and below the notch 13 is formed an aperture by securing transversely of and about midway the length of the notch 13, and to the inner side of the tube 5, the segmental rod or wire 15; said rod or wire forming a tension for the twine, as hereinafter explained in the operation of the device. A short cylindrical tube 16 corresponds internally with the external diameter of the cylindrical tube 5, and a weight 17 fits snugly and is adapted to reciprocate within the tube 5, and is provided with a vertical groove 18, which conforms to and embraces snugly the longitudinal and inwardly projecting guide-rib 19 of the tube, which is provided by bending the tube to 90 form the external groove 6. To operatively mount or connect these various parts so as to form a twine-holder, the end of the twine is passed vertically downward through the tube 16, and also through the paste-board tube 95 upon which said twine is wound, and is then threaded from the outside through the aperture below the notch 13. It is then brought back over the segmental rod 15 forming the upper side of said aperture. The tube is now 100 up-ended so as to cause the weight to slide within the tube and present its eye 19 opposite said aperture. The twine is now again threaded through the said aperture, the eye

of the weight, and through the notch 14 in the opposite side of the tube, and after sufficient twine has been drawn through it is carried through the space 4, and is threaded through the eye 7 at the lower end of the tube 5, and occupies the longitudinally extending groove 6. The tube upon which the twine is wound is now slipped down upon the shell 3, and the short tube 16 is moved vertically down within the twine-tube, and externally engages the upper end of the tube 5, and is held in such position by resting upon the upper end of the shell 3, as clearly shown in Fig. 2. The tube 5, is now moved laterally through the opening 12 of the plate 11, and then vertically downward until the shell 3 fits tightly upon the conical supporting-plate 11, which is carried by the above-mentioned bracket 8.

The operation of the device is as follows: 20 When it is necessary to tie a package, the clerk, grasping the free end of the twine, pulls downward thereon and raises the weight 17 to the upper end of the tube 6, and at the same time the necessary twine is fed through the eye of said tube to the operator from the ball of twine; the tension-rod 15, which is encircled by the twine, preventing the twine unwinding, from the ball too freely and easily. Immediately the clerk breaks the twine the 30 weight by gravity descends to the lower end of the tube and withdraws or raises the free or pendent end of the twine above the counter and out of the way of the clerk.

From the above description, it will be apparent that I have produced a twine-holder which is easy of manipulation, which removes automatically the dangling portion of the twine out of the way of the clerk, and which is simple, durable, and inexpensive of construction.

Having thus described my invention, what I claim as new, and desire to secure by Letters Patent, is—

1. A twine-holder, comprising a suspension frame having a segmental supporting-plate, a frusto-conical and tubular shell fitting upon said plate, and a tube inclosed and carried by said shell, and having a tension-rod, and a longitudinal groove in its outer side, a conical tube upon which the twine or cord is wound, fitting upon the frusto-conical shell, a short tube surrounding the upper end of the tube

having the longitudinal groove, and surrounded by the upper end of the conical tube of the ball of twine, a sliding weight carried 55 by the tube having the longitudinal groove and having an eye at its upper end, all arranged substantially as set forth.

2. In a twine-holder, the combination with a vertical tube carrying a tubular and frusto-conical shell, a weight within said tube, an eye carried at the lower end and outer side of said tube, and a bracket suspended from the ceiling having a segmental plate upon which the lower end of the frusto-conical 65 shell rests, and having a passage or opening in its side through which the vertical tube is inserted, of a conical tube upon which the twine is wound, which fits upon the frusto-conical shell, and a tube carried upon the 70 upper end of the vertical tube through which the cord is adapted to be guided, and also through the eye of the weight located in the vertical tube, and through the longitudinal groove of an eye carried by said tube, substantially as set forth.

3. In a twine-holder, the combination with a supporting bracket, a vertical and externally grooved tube having notches in its upper margin, a tension-rod extending transversely of one of said notches to form an aperture, a frusto-conical shell surrounding and secured to the tube near its upper end, and having an opening opposite the external groove of the vertical tube; said shell being 85 carried by the supporting bracket, a short tube fitting upon the upper end of the vertical tube and closing the notches thereof, and a weight having an eye, fitting reciprocally within the vertical tube, of a twine-carrying 90 tube fitting upon the shell and inclosing the lower end of the short tube, the strand from the twine wound upon said tube extending down through the short tube, around the tension-rod, through the eye of the weight, 95 through the opposite notch, and pendent downward, substantially as set forth.

In testimony whereof I affix my signature in presence of two witnesses.

AUGUST H. SCHWAN.
